US0D1032292S

(12) **United States Design Patent** (10) **Patent No.:** **US D1,032,292 S**
(45) **Date of Patent:** **** Jun. 25, 2024**

(54) **STRAW CUP**

(71) Applicant: **Elgin Chan**, Guangzhou (CN)

(72) Inventor: **Elgin Chan**, Guangzhou (CN)

(**) Term: **15 Years**

(21) Appl. No.: **29/813,380**

(22) Filed: **Oct. 28, 2021**

(51) LOC (14) Cl. **07-01**

(52) U.S. Cl.

USPC **D7/510; D7/532**

(58) **Field of Classification Search**

CLAIM

The ornamental design for a straw cup, as shown and described.

DESCRIPTION

FIG. 1 is a perspective view of my new design for a straw cup;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

1 Claim, 7 Drawing Sheets
